CLAIM

The ornamental design for a bus connector plug, as shown and described.

DESCRIPTION

FIG. 1 is a front perspective view of a bus connector plug showing our new design;

FIG. 2 is a front view thereof;

FIG. 3 is a top view thereof;

FIG. 4 is a left view thereof, the right view being a mirror image of same;

FIG. 5 is a bottom view thereof; and,

FIG. 6 is back view thereof.

The broken lines in the drawing figures show portions of the bus connector plug which form no part of the claimed design.

The shade lines in the figures show contour and not surface ornamentation.
